UNITED STATES PATENT OFFICE.

JAMES J. McCABE, OF NEW YORK, N. Y.

DESIGN FOR A FRAME FOR TAIL-STOCKS FOR LATHES.

SPECIFICATION forming part of Design No. 34,628, dated June 4, 1901.

Application filed May 1, 1901. Serial No. 58,395. Term of patent 14 years.

To all whom it may concern:

Be it known that I, JAMES J. McCABE, a citizen of the United States, residing at New York city, in the county and State of New York, have invented and produced a new and original Design for a Frame for a Tail-Stock for Lathes, of which the following is a specification, reference being had to the accompanying drawings, forming a part thereof, and in which—

Figure 1 is a top view of a frame for a tail-stock bearing and incorporating my design. Fig. 2 is a front elevation of same, and Fig. 3 is an end view of same.

The leading feature of my design consists of the form and configuration of the frame for a tail-stock, substantially as shown.

In the drawings, A designates the tail-stock frame as a whole, said frame comprising the base B, of rectangular outline, and the super-

posed body portion C, comprising the horizontal cylindrical portions D E, end webs F, and the web G, the latter being below the upper cylindrical portion E and extending downward from the same to the horizontal table portion H, which extends rearwardly from the upper edge of the cylindrical portion D, the whole being arranged and disposed substantially as illustrated in the drawings.

What I claim is—

The design for a frame for a tail-stock for lathes, substantially as shown and described.

Signed at New York, in the county and State of New York, this 30th day of April, 1901.

JAMES J. McCABE.
